UNITED STATES PATENT OFFICE.

EMIL GATHMANN, OF BALTIMORE, MARYLAND.

METHOD OF STRIPPING INGOTS FROM THEIR MOLDS AND APPARATUS THEREFOR.

1,059,667.

Specification of Letters Patent. Patented Apr. 22, 1913.

Application filed January 2, 1913. Serial No. 739,844.

To all whom it may concern:

Be it known that I, EMIL GATHMANN, a citizen of the United States, residing in Baltimore city, State of Maryland, have 5 invented certain new and useful Improvements in Methods of Stripping Ingots from Their Molds and in Apparatus Therefor, of which the following is a specification.

This invention relates particularly to the 10 manufacture of ingots in which molten metal is poured into a mold having a chamber larger in diameter at the top than at the bottom. Heretofore after the ingot has partially solidified in such molds, it has 15 been customary to reverse or turn the mold with the contained ingot upside down and then lift the mold away from the ingot, but this operation besides being difficult results in the formation of pipe in the body of the 20 ingot producing flaws in the final product.

The primary object of my invention is to provide an efficient way of withdrawing the ingot from the mold without reversing it. To accomplish this result I form an 25 opening in the bottom of the mold and arrange therein an ingot lifter which projects downwardly from the mold into an opening formed in the mold stool or support. The lifter is adapted to move vertically 30 relatively to the mold and when so moved to lift the ingot until its upper end projects sufficiently above the top of the mold to allow grippers to engage it and entirely withdraw the ingot from the mold. After 35 the ingot is cast and sufficiently solidified, the mold, with its contained ingot and the lifter thereunder, are lifted from the truck or support on which they are carried with the lifter projecting downwardly from the 40 bottom of the mold and then they are lowered upon a support which engages the bottom of the ingot lifter, then the mold is either allowed to further descend by gravity or is forced downward by mechanism which 45 preferably engages the mold near its upper end. In this way the upper part of the ingot is moved out of the mold and may be engaged by grippers of usual construction which withdraw it entirely from the mold 50 and carry it away. When the mold is thus forced down by power great strain is produced on the truck or support beneath if some provision is not made for preventing it, and in order to relieve this strain I provide means which so hold the mold during 55 the stripping operation that such pressure

is received by hangers which engage the mold stool. It will thus be observed that in accordance with my method I do not merely drop the mold over an ingot lifter or ejector, but I lower the mold gently and force it slowly but with any desired degree of pressure downward until the ingot is raised to the requisite extent in the mold chamber, and furthermore that I simultaneously apply power which raises or tends to raise the mold stool while the mold is being forced downward relatively to the stool.

In the accompanying drawings, Figure 1 70 is a diagrammatic sectional view showing mechanism embodying my improvements for stripping ingots. Fig. 2 is a view partly in side elevation and partly in section of parts of such mechanism. Fig. 3 is a perspective view of one of the mold stools. Fig. 4 is a view on an enlarged scale partly in elevation and partly in section of the stripping mechanism. Figs. 5 and 6 are detail views of modifications in which the 80 ingot lifter is provided with means for preventing it from being lifted out of the mold chamber with the ingot. Figs. 7, 8 and 9 are views showing further modifications.

Each mold A may be of any suitable construction, but is preferably of the form shown where the lower part is made relatively thick and the upper part relatively thin whereby the lower part of the ingot X is made to cool and solidify more rapidly 90 than the upper part thereof. The chamber of each mold is larger in diameter at the top than at the bottom and it is open at opposite ends. Through the bottom opening a of each mold projects an ingot lifter B 95 which also serves to seal the bottom of the mold chamber. The upper portion of the lifter is preferably tapered, as shown, to fit closely the correspondingly tapered opening a and a considerable portion of the 100 lifter projects below the bottom of the mold as indicated in Fig. 2.

It is customary to place the molds on trucks and to teem them while so supported and after teeming to move the truck to the 105 stripping mechanism. When trucks are thus used I preferably construct them in the way shown, i. e., each truck C is provided with a removable stool D which has a part d extending through an opening in 110 the platform of the truck and a flanged portion d' which rests on the platform.

- Each truck may carry any desired number of molds. In Fig. 2 four molds are shown on the truck, but this number may be varied within reasonable limits. Each stool 5 D is also formed with upwardly projecting arms d^2 having laterally projecting lugs d^3 for a purpose hereinafter described. It will be observed that each stool is formed with a part d^4 adapted to receive the ingot lifter D 10 in the manner indicated in Fig. 2.
- The traveling crane, shown in Fig. 1, is of well known construction. The part E is constructed to travel on suitably supported rails e while the part F travels on rails e' 15 arranged at right angles to the rails e. The apparatus F is similar in many respects to that heretofore used in ingot stripping plants, i. e., there is a truck f supporting a motor f' and a windlass f². The casing f³ 20 depending from the truck is adapted to contain lifting mechanism which it is not necessary to illustrate. It is sufficient to say that a rod G, which is threaded at its upper end (g) carries at its lower end a yoke H comprising arms h which are adapted to engage lugs a' on the neck of the mold. The rod may be raised and lowered by the mechanism indicated and thus raise and lower the mold. It will be observed that the arms h 25 are so formed on their lower ends as to so engage the lugs a' that the mold is not only raised and lowered, but on the downward movement of the rod the mold is not merely lowered but is forced downward positively 30 so that in the stripping operation if the ingot tends to stick in the mold it will be separated therefrom by reason of the additional pressure thus employed. Ordinarily the weight of the mold is sufficient, but if 35 40 there are imperfections in the mold due to any roughness or irregularities in the mold chamber, the weight of the mold itself is insufficient to effect the separation of the ingot and so it has sometimes been the practice to 45 drop the mold suddenly to effect the desired separation but this dropping of the mold imparts undesirable strains to the mold support which, by my improvements, are avoided.
- The rod G extends through a yoke I to which are pivotally connected hangers J having at their lower ends loops j adapted to engage the lugs d^3 of the mold stool D. It is not necessary, however, always to employ 55 these hangers as frequently the ingot may be raised in the mold by merely lowering it on the ingot lifter slowly and without imparting any strains on the truck and I have provided mechanism by which the hangers 60 J may be held out of operative position or may be brought into engagement with the stool when required. For this purpose I preferably employ cables L, L' which are connected, in the manner shown in the drawings, to the hangers and also connected with 65

suitable operating mechanism on the traveling truck f of the crane.

In Fig. 1 I have shown mechanism M, of well known construction which may be employed for engaging the upper end of the ingot after it is raised from the mold and for entirely withdrawing the ingot from the mold, such mechanism being also employed for conveying the ingot to a soaking or reheating pit or to any other desired place. 70 The ingots are cast in the molds A when supported by trucks C with the ingot lifters B in their lowermost position, as shown at the left hand side of Fig. 2. After the casting operation the truck is moved to the stripping plant, the lifting yoke H being so constructed, as shown in Fig. 1, that it may be made to engage the lugs a' of the mold by merely moving the truck properly over its supporting rails. When the lifting yoke thus engages the mold the former is raised so as to withdraw the lifter B from the stool D and then the truck is shifted until the lifter is disposed above the part d^4 of the stool, then the mold is lowered and the ingot is 75 raised relatively to the mold, in the manner indicated in Fig. 2, inasmuch as the lifter remains stationary at this time. If necessary, when the mold is being lowered, the requisite pressure may be applied to it downwardly to cause the separation of the mold and ingot. If such additional pressure is very great, or of such nature that it would place undue strain on the truck, the hangers J are brought into operation. This may be 80 done by suitably operating the cables L, L' and when the hangers engage the stool, in the manner indicated in Figs. 1 and 4, the downward thrust imparted to the mold by the rod G is received ultimately by the hangers J and thus the truck may be entirely relieved from pressure. 85

It sometimes happens that the ingot lifter will adhere to the ingot when the latter is being lifted out of the mold. To prevent this I may use a pin N which projects horizontally through the lower end of the lifter and is received in a recess n in the bottom of the mold, or I may use a collar or plate O, as indicated in Fig. 6. The apparatus may 90 be somewhat simplified thus,—the yoke for raising or lowering the mold may be of the form shown at P in Figs. 7, 8, and 9. In this case the lugs a' of the mold enter recesses formed in the arms p of the yoke and instead of employing a lifter of the kind shown at B, I may provide the mold with a suitable sealing stool and may use a separate lifter, such as shown at S in Fig. 8. 95

I claim as my invention:

1. The method herein described of stripping ingots, which consists in raising a mold with its contained ingot and with an ingot lifter projecting from the lower end of the mold, lowering the mold, ingot and lifter 100

onto a support which causes the lifter to raise the ingot partway out of the mold chamber, pressing the mold downwardly while the ingot is being raised within it and 5 then gripping the upper part of the ingot and lifting it out of the mold.

2. The method herein described of stripping ingots, which consists in raising the mold with its contained ingot from their 10 support, pushing the ingot upwardly in the mold and simultaneously pressing the mold downwardly while the lifter is raising the ingot and then gripping the upper part of the ingot and lifting it out of the mold.

15 3. The method herein described of stripping ingots from molds having separable stools, which consists in raising the mold with its contained ingot from the stool, lowering the mold and ingot over an ingot lifter 20 supported by the stool which raises the ingot part-way out of the mold, simultaneously applying upward pressure to the stool to relieve the mold support of strain and then gripping the upper part of the ingot and 25 lifting it out of the mold.

4. An ingot lifter adapted to engage the bottom of an ingot and means adapted to engage the mold to lift, lower and press it positively downward on the ingot lifter.

30 5. The combination with a mold provided with an ingot lifter, of arms engaging the mold and means for operating the arms to lift the mold and to lower and press it positively downward.

35 6. The combination of a mold provided with an ingot lifter and having laterally projecting lugs, of a yoke comprising arms adapted to engage said lugs, and means for raising and lowering the yoke to raise the 40 mold, to lower it and to press it positively downward.

45 7. The combination of a mold having a vertically moving ingot lifter at its lower end and provided with laterally projecting lugs at its upper end, a yoke engaging the lugs on their upper and lower surfaces and means for lifting the yoke and for slowly

lowering it for pressing the mold downward.

8. The combination of a mold, a mold 50 support, a stool carried by the support on which the mold rests, an ingot lifter vertically movable in the mold extending from the bottom thereof and projecting into the mold chamber, means for raising the mold 55 with the ingot lifter away from the stool, and means for pushing the mold positively downward while the lifter is pushing the ingot upward.

9. The combination of a mold, means for 60 raising and lowering it, an ingot lifter, means for pushing the mold downward over the lifter, and means for drawing the lifter upward.

10. The combination of a mold support, a 65 mold, a stool interposed between the mold and the support and which is separable from the mold and from the support, means for raising and lowering the mold, an ingot lifter supported at times by the stool, means 70 for raising and lowering the mold and means for supporting the mold stool while the mold is being lowered.

11. The combination with an ingot mold having an opening in its lower end, of an ingot lifter projecting through said opening 75 and means on the lower end of said lifter for limiting its upward movement in the mold chamber.

12. The combination with a mold having 80 an opening in its lower end, an ingot lifter projecting through said opening and sealing it, a stool having an opening through which the ingot lifter extends and a support for said lifter when the mold is raised, 85 means for raising and lowering the mold, hangers separably connected with the stool and means for operating said hangers.

In testimony whereof, I have hereunto subscribed my name.

EMIL GATHMANN.
